NATURAL FREQUENCY VIBRATING
CONVEYERElmer J. Renner, Aurora, Ill., assignor to
Stephens-Adamson Mfg. Co., a corporation of
Illinois

Application May 24, 1950, Serial No. 164,014

3 Claims. (Cl. 198—220)

1

The principal object of this invention is to convey loose, discrete material in a substantially continuous, wavy stream along a tray or table.

Generally speaking, this is accomplished by pivotally connecting a tray and a counterbalance for substantial parallel motion on opposite sides of supporting fulcra, interposing harmonic spring elements between them, and giving one of them harmonic vibration whereby the tray is given balanced vibration in substantially the natural period of harmonic spring elements.

Further objects and advantages of the invention will appear as the disclosure proceeds and the description is read in connection with the accompanying diagrammatic drawings, in which:

Fig. 1 is a side elevation of one embodiment of the invention;

Fig. 2 is a longitudinal central vertical section of the left end portion of Fig. 1;

Fig. 3 is an end view looking from the right in Fig. 1;

Fig. 4 is a section on the line 4—4 of Fig. 2;

Fig. 5 is an axial section through one of the pivotal connections;

Fig. 6 is a side elevation of another embodiment of the invention;

Fig. 7 is an enlarged side elevation of one unit shown in Fig. 6 arranged to incline the tray at a slight angle;

Fig. 8 is a plan view of a carrier support used in Figs. 6 and 7; and

Fig. 9 is a sketch indicating how the spring units 16 vibrate at the end portions and leave the middle practically neutral.

The tray 10 and counterbalance 11 are connected by four links or levers 12 pivoted at opposite ends to the tray and the counterbalance and fulcrumed between them at 13 in bearings supported by brackets 14 on a base frame 15. This gives the tray and the counterbalance parallel motion in moving toward and away from each other while the levers swing on the fulcra.

The tray and the counterbalance are connected by spring elements, here shown as helical springs 16 aligned longitudinally with the tray and the counterbalance and inclined with respect to the tray and the counterbalance.

Harmonic motion is given to the tray by a connecting rod 17 pivoted to the tray 10 at 18 on its center line and driven by an eccentric 19 on a shaft 20, in turn driven by a motor 21 through a belt 22 and suitable pulleys.

The essential assembly of the tray and counterbalance, mounted on the rocking arms or links after the fashion of parallel motion and connected

2

by helical springs, which resist any change in the distance between them, seems to be the nub of the apparatus. The harmonic drive of the eccentric forces the balanced units apart, then together at each revolution; and during each of which the helical springs offer resistance in both directions. The timing of the drive fits in with the natural period of vibration of the springs and develops a harmonic action in the end portions of the springs, leaving the intermediate or practically middle portion neutral (Fig. 9). Each time the throw of the eccentric moves the tray, the springs are compressed or extended with harmonic motion, which tends to reverse itself in time with the rotation of the eccentric.

This arrangement gives the desired vibratory movement to the tray and the counterbalance (which may also be a tray for conveying the material), and does so with a minimum of power input.

The pivots 24 between the ends of the links or levers 12 and the tray and counterbalance are preferably in substantially the form shown in Fig. 5. Actually, the pivoting is about a shaft 26 having a shoulder 27, a bearing portion 28, and a threaded portion 29 at each end. The bearing portion is received within a hollow bearing portion 30 at the end of each link or lever. Those bearing portions are spaced radially to receive rubber blocks 31 of double frusto-conical shape, compressed between those bearing portions and between disks 32 by a nut 33. Thus, the actual bearing is on rubber under compression, and the rotary motion between the pivots and the shaft 26 is of such relatively small angularity that the energy absorption is very low, although the rubber does do some work in resisting any relative movement between the tray and the counterbalance, and tending to always return them to normal position.

The bearings of the fulcra 13 are about a shaft 36 and are of the same character as that shown in Fig. 5, but appropriately larger because those bearings must carry the entire weight of both the tray, the counterbalance, the links, and the springs, etc.

Each end of each spring 16 is fitted with a cylindrical block 40 of rubber of durometer hardness on the order of 10, which is compressed between disks 41 having curved edges 42, and drawn together by a bolt and a nut 43. Compression of the blocks 40 shortens them in the middle area 44, but extends them circumferentially in the area 45 within the end convolutions 46 of the spring 16. This has the effect of a yieldable connec-

tion between the bolts 43 and the ends of the springs.

Spring assemblies of that order are made up to length and assembled with the tray and the counterbalance by projecting portions of the bolts 43 extending through openings 47 in brackets 48 fixed to the tray and the counterbalance respectively. They are made fast by nuts 49 which clamp the brackets against the outer disks 41. This connection between the springs and the tray and the counterbalance gives the spring elements between the brackets 48 a definite length, and at the same time gives the spacing between the tray and the counterbalance a definite length. Any change in the spacing requires a change in the effective length of the spring elements; and, when coupled with harmonic motion, the effect is as above described.

While the features here disclosed will be varied according to the circumstances and individual preferences, a design that has been found satisfactory has the following dimensions:

The tray is 10 feet long and concave upwardly; 14 inches wide inside on a radius of $7\frac{3}{4}$ inches. The counterbalance is 8 feet and 6 inches long; 1 foot $2\frac{1}{2}$ inches wide. The frame is 11 feet $3\frac{1}{8}$ inches long; 1 foot 9 inches wide, inside. The links or levers 12 are 1 foot $\frac{1}{8}$ inch long between centers. The eccentric is $\frac{1}{8}$ of an inch off center and 1.4375 inches in diameter. The motor is $\frac{1}{4}$ hp., 1600 R. P. M., and the drive gives the eccentric 815 R. P. M. This combination produces a conveying speed of 75 F. P. M.

In the embodiment shown in Figs. 6, 7 and 8, the base frame 15 is replaced by two carrier supports, generally indicated by 50 and 51. The carrier support 50 is a relatively short, forked frame having brackets 52 at the front end to receive the fulcra of the levers 12 in bearings 53, and having a platform 54 on which the power unit is mounted.

The carrier supports 51 are composed mainly of brackets 55 having bearings 56 for the shaft 12 and cross connected in any suitable manner to hold them together.

Both of the carrier supports are equipped with rubber feet 57.

The carrier supports merely act as supports and do not have to be tied together or fastened down. They require very much less material than the base frame 15 and cost less to manufacture.

The embodiment shown in Figs. 6 and 7 includes separate units, indicated generally by 60 and 61, connected together by bolts and flanges, generally indicated at 62. In this way, the conveyor can be made to any suitable length.

The units 60 are shown without power, although they could be so equipped. Unit 61 is identical with 60 except it is equipped with a power drive. Two or three non-powered units may be connected by the bolted flange 62 to one powered unit to give a conveyor length of 30 to 40 feet. Longer units can be made by inserting power units at

every fourth section, thus continuing the conveyor to any desired length.

Conveyors embodying the invention will handle any sort of discrete material and it has been found that they will convey finely powdered or pulverulent materials. By inclining the tray two or more degrees, substantially as illustrated in Fig. 7, finely powdered materials will flow as a liquid down the tray, probably because it becomes fluent with the mixture of air.

The inclination is here produced by providing the power unit 50 with feet 63 and 64 of different height, but the inclination can be worked out in various ways.

While two springs 16 are shown in all the forms here illustrated, one, or any plurality of springs, may be used according to the circumstances.

I claim:

1. In a vibrating conveyor, a conveyor tray element, a balancing element spaced from the tray element, rigid levers having their opposite ends pivotally connected to said elements and fulcrumed between them on a fixed support, means for vibrating said elements, and helical spring means having its opposite ends directly connected to the tray element and balancing element and being unstressed at mid-stroke and acting alternately in compression and tension during each half cycle.

2. In a vibrating conveyor, a conveyor tray element, a balancing element spaced from the tray element, rigid levers having their opposite ends pivotally connected to said elements and fulcrumed between them on a fixed support, helical spring means having its opposite ends directly connected to the tray element and balancing element, and means for vibrating said elements at the natural frequency of said helical spring means, said helical spring means being unstressed at mid-stroke and acting alternately in compression and tension during each half cycle.

3. In a vibrating conveyor, a conveyor tray element, a balancing element spaced from the tray element, rigid levers having their opposite ends pivotally connected to said elements and fulcrumed between them on a fixed support means for vibrating said elements, and helical spring means diagonally disposed between said elements and having its opposite ends directly connected to the tray element and balancing element and being unstressed at mid-stroke and acting alternately in compression and tension during each half cycle.

ELMER J. RENNER.
